UNITED STATES PATENT OFFICE.

HENRY W. CAREY, OF MANISTEE, MICHIGAN.

BAND FOR SHINGLE-BUNCHES.

SPECIFICATION forming part of Letters Patent No. 286,586, dated October 9, 1883.

Application filed June 11, 1883. (No model.)

To all whom it may concern:

Be it known that I, HENRY W. CAREY, of Manistee, in the county of Manistee and State of Michigan, have invented a new and useful Improvement in Shingle-Bands; and I do hereby declare that the following is a full and exact description of the same, reference being had to the accompanying drawings, and to the letters of reference marked thereon.

10. My invention relates to an improvement in shingle-bands.

The object of the invention is to produce a band of increased strength with an economy in the use of material and in the amount of time usually consumed in fastening such band to the strips of wood ordinarily employed in binding shingles. This I accomplish by the use of a flat strip of metal bent near each end at a right angle in parallel directions, and provided with two slots cut in the edges of each of said bent portions at points diametrically opposite, and through which slots pass staples, by which the band thus constructed is secured to the wooden strips hereinbefore referred to.

25. For the better understanding of the invention reference will be made to the accompanying sheet of drawings, in which—

Figure 1 represents a bundle of shingles held together by my improved band, and Fig. 30. 2 a view in detail of said band.

Like letters refer to corresponding parts in both views.

In the drawings, A represents the shingles, which are arranged with respect to one another in the ordinary way; and B, one of the wooden strips ordinarily employed in binding said shingles. These wooden strips B are of any desired form, and occupy a position about the center of the bundle. There is one 35 upon each side of the bundle, and they are of sufficient length to extend a short distance beyond each end of the same.

C represents my improved band. (Shown clearly in Fig. 2 of the drawings.) As there 40 shown, it consists of a flat metal strip bent near each end at right angles, and provided

upon the edges of such bent portions with suitable slots, a a, through which the ends of staples D are passed. These slots may be of any desired or suitable form. After the 50 staples D have been inserted into the slots a, their pointed ends are driven into the wooden strips B, around the ends of which the strips C are bent, as shown.

The advantages I assert for my band over 55 those now in use are—

First, that by providing said strips with the slots arranged diametrically opposite one another but a small portion of the band is required to be bent around the wooden strips, 60 and thus a saving of material is accomplished. I have found that at least fifteen per cent. of material is saved.

Second, by substituting these slots for the nail-holes ordinarily formed in the ends of the 65 bands a stronger band is secured.

Third, by the substitution of the staples for nails the bands are more easily secured around the bundle, and much time saved.

Having thus described my invention, what 70 I claim as new therein, and for which I desire to secure Letters Patent, is—

1. An improved shingle-band, consisting of a flat metal strip bent at each end, and provided upon the edges of said bent portions 75 with suitable slots, substantially as and for the purpose set forth.

2. The shingle-band described, consisting of a flat strip of metal bent near each end at a right angle in parallel directions, and provided at points, diametrically opposite upon the edges of each of said bent portions with two slots, through which pass staples to secure said band to the wooden strips employed in binding shingles, as set forth. 85

In testimony whereof I affix my signature in presence of two witnesses.

HENRY W. CAREY.

Witnesses:

FRANK H. SMITH,
CHARLES W. GLOVER.
